UNITED STATES PATENT OFFICE.

ERNEST C. COOK, OF CHICAGO, ILLINOIS.

DESIGN FOR A PHONOGRAPH-CABINET.

53,628.

Specification for Design.

Patented July 22, 1919.

Application filed February 26, 1919. Serial No. 279,455. Term of patent 14 years.

To all whom it may concern:

Be it known that I, ERNEST C. COOK, a citizen of the United States, residing at Chicago, in the county of Cook and State of Illinois, have invented a new, original, and ornamental Design for a Phonograph-Cabinet, of which the following is a specification, reference being had to the accompanying drawing, forming part thereof.

The figure is a perspective view of a phonograph cabinet showing my new design.

I claim:

The ornamental design for a phonograph cabinet as shown.

ERNEST C. COOK.
